UNITED STATES PATENT OFFICE.

FRITZ GEORGE HOBERG, OF WOONSOCKET, RHODE ISLAND.

MACHINE FOR AUTOMATICALLY ASSEMBLING WIRE HEDDLES.

1,355,670.

Specification of Letters Patent.

Patented Oct. 12, 1920.

Application filed May 14, 1920. Serial No. 381,401.

To all whom it may concern:

Be it known that I, FRITZ GEORGE HOBERG, citizen of the United States, residing at Woonsocket, in the county of Providence and State of Rhode Island, have invented 5 certain new and useful Improvements in Machines for Automatically Assembling Wire Heddles, of which the following is a specification.

10 The usual method practised in assembling wire heddles with the cross bars of a heddle-frame, used in looms, is for girl operatives to thread or string said heddles on said cross bars, by hand. This is very laborious, 15 consumes considerable time, and is expensive.

So far as I am aware, no machine has ever been devised for automatically assembling the heddles on the cross bars of a heddle-frame.

20 The object, therefore, of my invention is to provide such a machine.

A further object is to provide such a machine which shall be compact and simple 25 in its organization, and positive and reliable in operation.

With these objects in view, the invention resides, generally stated, in a machine comprising the combination of means for supporting the heddle frame-bars on which the heddles are to be strung, a reservoir or 30 hopper for holding a supply of heddles, rotating carriers disposed beneath said hopper and in the line of fall or descent of said 35 heddles after discharge therefrom, for conveying said heddles to said heddle frame-bars, means for feeding the heddles, successively, from said hopper in timed relation with the movement of said carriers, 40 and means coöperating with said carriers for preventing accidental disengagement of said heddles therefrom and for presenting the same with the eyes thereof in proper position to be engaged by said frame-bars.

45 The invention also resides in certain novel structural features going to make up the ultimate perfection of the machine as an 50 entirety; such, for instance, as a peculiar form of cam for elevating the hopper feed-slide and for giving the same a shaking or jarring movement while at its highest point of elevation, so as to cause the heddle to drop therefrom onto the rotary carriers.

55 The accompanying drawings, forming part of my specification, clearly disclose an exemplary form of embodiment of the

underlying principles of my invention. Like reference characters designate corresponding parts throughout the several views. Briefly described:

60

Figure 1 is a view in front elevation of my machine;

Fig. 2 is a view in side elevation thereof, looking at the right-hand side of Fig. 1;

Fig. 3 is a fragmentary sectional view on 65 the line 3—3, Fig. 1, looking in the direction of the arrows, showing the position of the parts when the slide is at its lowest point;

Fig. 4 is a fragmentary sectional view, taken on the same line 3—3 of Fig. 1, showing 70 the position of the parts when the slide is at its highest point; and

Figs. 5 and 6 are fragmentary detail views showing more particularly the spring tension means coöperating with the rotating 75 carrier (shown in dotted lines), the latter being shown in said figures at different stages in its rotation and as having moved the heddle from the position shown in Fig. 5 to that shown in Fig. 6.

80

Reference may now be had, in detail, to the drawings:

The working parts of my machine may preferably be disposed or supported upon a pedestal 1, desirably hollow, for the sake 85 of lightness, and provided in its front wall, at the top thereof, with an opening 5 extending substantially from side to side of said wall.

Supported at the top of the pedestal, 90 above said opening 5, is an elongated hopper or reservoir 6 of the usual transverse V-form, as shown in Fig. 3.

Disposed against the inner surface of the front inclined wall of said hopper, and extending the length thereof, is a metallic strip or plate 7 bent, at its lower end, as shown at 8, said bent portion projecting into the exit end of said hopper, so as to obstruct, to a certain extent, passage there-through, and permit passage of one heddle, only, at one time.

95 The bottom 9 of the hopper is, as shown in Fig. 3, inclined downward and forward, so as to cause a free movement of the heddles B along said bottom and through the exit end of the hopper.

100 The base 10 of the hopper is provided with a front vertical wall 11, in the same vertical plane as the front face of the bent portion 8 of the inclined plate 7.

105

110 Disposed against said hopper base wall

11 is a vertically disposed and vertically reciprocable slide 12, provided with a beveled top 13, which, when the slide is in its lowest position, constitutes an extension of 5 the inclined bottom 9 of the hopper, as seen in Fig. 3.

A stationary gate 14 is disposed against the front surface of the slide 12, and has a beveled top 15. As shown, said gate is preferably 10 a metallic strip or plate. The gate is of such a width, or is so positioned relative to the slide 12, that the latter, when at its lowest point of movement, is below the top of the gate, as seen in Fig. 3, and, when 15 at its highest point of movement, the inclined top 13 thereof is flush with the beveled top 15 of the gate, as seen in Fig. 4.

It will be noted that the slide 12 is disposed between the base wall 11 of the hopper 20 and said gate 14, and is guided in its reciprocation therebetween.

Disposed in cut-away portions in the lower part of the slide 12, which cut-away portions register with corresponding cut-away 25 portions in the gate 14, are rollers 16, 16 revolutely mounted on axles 17, 17 supported by said slide.

Projecting through the side walls of the pedestal 1, near the top thereof, is a revolvable shaft 18 carrying fast on one exteriorly 30 projecting end a gear-wheel 19 meshing with a worm 20 on a counter-shaft 21 suitably supported in bearings 22, 22 carried by the pedestal 1. Fast on said shaft 21, at one end thereof, is a belt-wheel or drum 23, over which passes an endless belt (not shown) 35 driven from a power wheel or pulley (not shown).

Fast on said shaft 18 and frictionally engaging the rollers 16, 16 are cams 24, 24, provided, at their highest points with successive scallops, or curved grooves, 25, 25, at least two of said grooves being provided for 45 each of said highest points of each cam, for a purpose presently appearing.

Also fast on said shaft 18, at points thereon in proximity to the upper ends of the heddle-bars A, A, are carrier-rolls 26, 26, each of which is, as shown, peculiarly 50 formed; *i. e.*, it has a plurality of peripherally-cut away portions, each of which provides said roll with a peripheral flat surface 27, a curved recess 28 at one end of said flat surface, and a wall 29 disposed substantially 55 at right angles to the plane of said flat surface and radially disposed with reference to the axis of rotation of said roll. As shown in Fig. 1, there are two parallel series of said cut-away portions. Each of said rolls is 60 also provided with two peripheral, circumferential grooves 30, 30, concentric with the axis of rotation of said roll. The tops of the heddle-bars A, A are positioned in one 65 of said grooves 30, preferably the outer one; and upper and lower leaf-springs 31, 32,

respectively, are disposed in the other groove. As shown, the leaf spring 32 is relatively long, and is supported at both ends in brackets 33, 33, one of which is adjustably secured to the front wall of the pedestal 1 70 by a set-screw 34 passing through a longitudinally-extending slot 35 in the bracket, and the other of which is adjustably secured to the under surface of the top of the machine by a similar set-screw 34 passing 75 through a like slot in this bracket. The brackets 33, 33 are, as shown in Fig. 3, in planes at right angles to each other, one of said brackets being above and to one side of the other bracket, so that the 80 spring 32 supported by said brackets is held in a bowed position, said spring curving over and bearing against the carrier-roll 26.

The springs 31 are held in a pendent position from brackets 36 carried by the sides 85 of the pedestal 1, toward the top thereof and adjacent the lower ends of the hopper 6. Each of said springs 31 has a lower, longitudinally curved portion 37 conforming to the curvature of the spring 32 and bearing 90 thereon.

In operation, the shaft 18 will be revolved by reason of its geared connections with the shaft 21 driven from the belt-wheel 23. Through the cams 24 fast on the revolving 95 shaft 18, the slide 12 will be raised, thus carrying with it the heddle-wire B resting thereon, until the highest point of the cam is reached, at which time the lower edge of the inclined top 13 of the slide 12 will be 100 substantially flush with the top of the gate 14, whereupon the shallow curved grooves 25, 25 will give the slide 12 a jarring motion to insure the heddle-wire B passing therefrom over the gate 14, whence it falls onto 105 one of the arcuate or sector-shaped peripheral portions of the rolls 26. At this point in the operation, the position of the moving parts will be as shown in Fig. 4. The heddle-wire B rests upon this curved portion 26' of the rolls 26, 26, and, in the continued movement of the rolls, the inclined straight peripheral surface 27 of said rolls moves beneath said heddle and out of contact therewith, leaving the same supported 110 upon the springs 32, as shown in Fig. 6. Then, as the rolls continue their revolution, the wall 29 rides into contact with the heddle-wire B and pushes the same between the 115 springs 27, 32, as shown in Fig. 5, thus separating said springs slightly, and carrying the heddle-wire around until the top of the heddle-bars A, A passes through the end eyes of the heddle-wire, whereupon the latter falls by gravity down the vertically- 120 disposed heddle frame-bars A, A, as shown 125 in Fig. 1.

Suitable means are provided for supporting the heddle frame-bars A, A in proper operative position with respect to the car- 130

rier-rolls 26, 26, so that the upper ends of said bars will be in the path of movement of the heddles A as they are carried around by said rolls and the lateral eyes b, b of the 5 heddles engaged with said upper ends of the frame-bars at a predetermined period in the rotation of said carrier-rolls. To this end, the front wall of the pedestal 1 carries, toward its lower end, two projections or bosses 10 2, 2, and each frame-bar A is provided, toward one end, with a longitudinally-extending slot 4, through which a set-screw 3 may pass for adjustably securing the bar A to said boss.

15 While I have described, with great particularity, a concrete embodiment of my invention, it is to be understood that the same is capable of modification, especially in detail, without departing from the spirit of 20 the invention, or necessarily sacrificing any of its advantages. All such changes as come within the scope of the appended claims are within the purview of the invention.

25 Having thus fully described my invention, what I claim as new and desire to secure by Letters Patent of the United States is:

1. A machine for assembling wire heddles with the cross frame-bars of a loom, comprising means for supporting said frame-bars, a reservoir for wire heddles, and mechanism for successively moving the wire heddles from said reservoir to said frame-bars and stringing said heddles thereon, said 35 mechanism including rotatable heddle-carrying means, and a reciprocating member for feeding said heddles from said hopper to said heddle-carrying means.

2. A machine for assembling wire heddles with the cross frame-bars of a loom, comprising means for supporting said frame-bars, a reservoir for wire heddles, and mechanism for successively moving the wire heddles from said reservoir to said frame-bars 45 and stringing said heddles thereon, said mechanism including rotatable heddle-carrying means, a reciprocating member for feeding said heddles from said hopper to said heddle-carrying means, and cam means 50 for actuating said reciprocating member.

3. A machine for assembling wire heddles with the cross frame-bars of a loom, comprising means for supporting said frame-bars, a hopper for wire heddles, a stationary 55 gate in proximity to the exit end of said hopper, and mechanism for successively moving the wire heddles from said reservoir to said frame-bars and stringing said heddles thereon, said mechanism including 60 rotatable heddle-carrying means, and a reciprocating member for feeding said heddles from said hopper over the top of said gate, onto said heddle-carrying means.

4. A machine for assembling wire heddles with the cross frame-bars of a loom, comprising means for supporting said frame-bars, a hopper for wire heddles, a stationary gate in proximity to the exit end of said hopper, and mechanism for successively moving the wire heddles from said reservoir to said frame-bars and stringing said heddles thereon, said mechanism including rotatable heddle-carrying means, a reciprocating member for feeding said heddles from said hopper over the top of said gate, 70 onto said heddle-carrying means, and cam means for actuating said reciprocating member.

5. A machine for assembling wire heddles with the cross frame-bars of a loom, comprising means for supporting said frame-bars, a hopper for wire heddles, a stationary gate in proximity to the exit end of said hopper, and mechanism for successively moving the wire heddles from said reservoir to said frame-bars and stringing said heddles thereon, said mechanism including rotatable heddle-carrying means, a reciprocating member for feeding said heddles from said hopper over the top of said gate, 80 onto said heddle-carrying means, and cam means for actuating said reciprocating member and formed to give said member a jarring motion at the limit of reciprocation 85 of said member in one direction.

6. A machine for assembling wire heddles with the cross frame-bars of a loom, comprising means for supporting said frame-bars, a hopper for wire heddles, and mechanism for successively moving the wire heddles from said hopper to said frame-bars and stringing said heddles thereon, said mechanism including rotating heddle-carrying members, and springs coöoperating with 90 said heddle-carrying members and between 95 which said heddles are moved in the rotation of said members.

7. A machine for assembling wire heddles with the cross frame-bars of a loom, comprising means for supporting said frame-bars, a hopper for wire heddles, and mechanism for successively moving the wire heddles from said hopper to said frame-bars and stringing said heddles thereon, said mechanism including rotating heddle-carrying members, a reciprocating member for feeding said heddles, successively, from said hopper to said heddle-carrying members, cam means for actuating said reciprocating member, and springs coöoperating with 100 said heddle-carrying members and between which 105 said heddles are moved in the rotation of said members.

In testimony whereof I affix my signature.

FRITZ GEORGE HOBERG.
